APPARATUS FOR HEATING BLAST FURNACE STOVES

George H. Krapf, Hazel Crest, Ill., assignor to United States Steel Corporation, a corporation of New Jersey
Filed Dec. 21, 1960, Ser. No. 77,350
4 Claims. (Cl. 263—19)

This invention relates to apparatus for heating stoves and particularly blast furnace stoves. The conventional blast furnace stove contains within the stove shell a combustion chamber extending from the top to the bottom of the stove shell. Attached to this combustion chamber is a gas furnace burner which mixes the gas and air and delivers this mixture into the combustion chamber where the fuel is burned. The combustion space occupies approximately 40% of the horizontal section within the stove shell so that the volume of stove checker brick that can be installed within the shell of the stove is reduced accordingly. In the past, attempts have been made to burn the blast furnace gas outside of the stove shell and to put the products of combustion into the dome of the stove. However, these attempts have failed for various reasons, including high installation cost, high maintenance cost and poor control of temperatures. It is also common to have the products of combustion pass through the stoves at atmospheric or essentially atmospheric pressures.

It is therefore an object of my invention to provide blast furnace stoves in which the majority of the space within the stove shell is utilized for checker work and in which the fuel is burned outside the stove with the products of combustion being introduced into the top of the stove.

Another object is to provide such a blast furnace stove in which the flow and temperature of the burnt gases is accurately controlled.

Still another object is to provide such a blast furnace stove in which the burnt gases are utilized to drive a gas turbine.

A further object is to provide such a stove in which the burnt gases are maintained at an elevated pressure within the stove.

These and other objects will be more apparent after referring to the following specification and attached drawing, in which:

FIGURE 1 is a schematic view of a blast furnace stove equipped with the apparatus of my invention; and

FIGURE 2 is an enlarged sectional view of a detail of my invention.

Referring more particularly to the drawings reference numeral 2 indicates the shell of a blast furnace stove. Checker brickwork 4 is installed in the shell 2 across the full cross section thereof and extends from a point adjacent the bottom of the shell to a point adjacent the top thereof. A space 6 is provided beneath the brickwork 4 and a space 8 above the brickwork. These spaces are kept at a minimum and are only sufficient to provide for the necessary conduit connections. The brickwork 4 is supported in any suitable manner such as by means of refractory arches. A cold air conduit 10 is connected to the bottom of the shell 2 into the space 6 and a conduit 12 is connected below the conduit 10. Shut off valves 14 and 16 are provided in the conduits 10 and 12, respectively. A hot air conduit 18 is connected to the shell 2 into the space 8. A shut off valve 20 is provided in the conduit 18. A cold air conduit 22 having a control valve 24 therein is connected in the conduit 18. A temperature responsive device 26 is provided in the conduit 18 and is connected to a control 28 which regulates the valve 24. An opening 30 is provided in

2

dome 32 of the shell 2 and a combustor 34 is mounted on top of the dome 32 over the opening 30. A shut off valve 36 is provided to close the opening 30. The combustor is a device wherein fuel is substantially all burned prior to its discharge therefrom. As shown combustor 34 consists of an outer shell 38 and a concentric inner shell basket 40 having openings or slots 42 therethrough. Combustion air is delivered into the space between the shells 38 and 40 through a conduit 44 having a shut off valve 46 therein. Preferably at least two openings are provided in shell 38 so as to provide for air flow around the shell 40. Fuel, preferably blast furnace gas, is introduced into the top of the inner shell 40 through a conduit 48 having a shut off valve 50 therein. Pilot fuel is introduced into the top of the combustor 34 through a conduit 52 having a shut off valve 54 therein. An igniter 56 is provided at the end of the conduit 52. Additional burners 57 may be provided at the top of combustor 34 for the introduction of auxiliary fuel when necessary. Combustion air is provided to the conduit 44 by means of an air compressor 58 and fuel is provided through the conduit 48 by means of a compressor 60. The compressors 58 and 60 are preferably of the axial flow type and are driven by means of a motor 62 and gas turbine 64. Inlet 66 of gas turbine 64 is connected to conduit 12. A branch conduit 68 is connected to inlet 66 and control valve 70 is provided therein. A control valve 72 is mounted in conduit 12 on the stack side of gas turbine inlet conduit 66. A control 74 is provided to operate the valves 70 and 72. A shut off valve 76 is provided in inlet conduit 66. A regulating valve 78 is provided in the conduit 12 on the stove side of inlet conduit 66. The position of valve 78 is controlled by means of a pressure control 80 having a pressure tap 82 connected to the conduit 12 on the stove side of valve 78. Pressure tap 82 may alternatively be connected to the bottom of the stove. A thermocouple or other temperature responsive device 84 is provided at the top of the checkerwork 4 and is connected to a control 86 for a valve 88 located in recycle conduit 90. A heat exchanger 92 is also provided in the conduit 90. A conduit 94, having a regulating valve 96 therein, connects conduits 44 and 66. The valve 96 is positioned by means of a control 98 which has a connection 100 to a flow determining means 102 in conduit 44 adjacent the compressor 58.

The compressors 58 and 60, gas turbine 64 and motor 62 may be used in conjunction with more than one stove. For that purpose conduit 44 has a branch conduit 44' leading to a second stove (not shown) with a shut off valve 104 being provided in the branch conduit 44'; the conduit 48 has a branch conduit 48' connected to the second stove with a shut off valve 106 being provided in the branch conduit 48'; and conduit 66 has a branch conduit 66' leading to the second stove with a shut off valve 108 being provided in the branch conduit 66'.

A thermocouple 110 or other temperature determining means is preferably provided in the space 6.

Assuming that blast air has been passing through the stove 2 and the temperature of the checker work therein has fallen to a point where the checkerwork 4 must be heated, the valves 14 and 20 are closed to stop the flow of air therethrough. If the air and fuel compressors 58 and 60 have been operating to heat another stove they are disconnected from that stove by closing valves 104, 106 and 108. If the motor 62 has not been operating it is started in operation to run compressors 58 and 60. Valve 88 is partially opened so that the fuel being compressed will flow around the control loop, including heat exchanger 92. During this time the position of valve

83 will be manually controlled. The valve 96 will also be manually positioned to control flow of air from compressor 58 through conduits 94 and 66 to gas turbine 64. Valves 46, 36, 16, 78 and 72 are then opened to permit flow of air through the stove 2 and out the stack. The setting of valve 96 controls the air flow through the stove. Electrical ignitor 56 is then energized and valve 54 opened to admit pilot fuel to the combustor 34. When a pilot flame is established as indicated by a standard flame detection device, not shown, the ignitor 56 will be deenergized. Blast furnace gas or other fuel is then admitted to the combustor 34 by opening valve 50. The amount of blast furnace gas furnished is established by setting valve 88 to the desired position. The combustor and stove are then brought to a pressurized condition by increasing the flow of blast furnace gas and air to the combustor 34 by further adjustment of valves 88 and 96 and by gradual movement of control valve 78 toward a closed position as determined by the pressure in conduit 12 until the desired pressure of at least two atmospheres absolute is obtained. The pressure is preferably maintained between two and four atmospheres absolute. The control 98 is set to deliver a predetermined flow of air to the combustor 34 and the desired heat input to the combustor is automatically controlled by the temperature sensitive device 84. During this period of initial operation control valve 70 will be gradually opened to atmosphere to satisfy the needs of the gas turbine 64.

To place the gas turbine 64 in operation, valve 76 is opened and valves 70 and 72 gradually closed by means of control 74. This will cause flow of burnt gases through conduit 66 to the gas turbine 64 so as to produce at least part of the energy required to operate the compressors 58 and 60. When the stove 2 has reached the desired temperature as indicated by the temperature sensitive device 110 the fuel is taken off by closing valves 50 and 54. The air is then taken off and the stove 2 isolated from the combustor 34 by closing valves 36 and 46. Valves 16 and 76 are also closed. Valves 14 and 20 are then opened to permit flow of cold air through the stove 2 where it is heated and then delivered through conduit 18 to the blast furnace. The temperature of the air delivered to the blast furnace is controlled by the opening or closing of valve 24 by means of control 28 so as to admit more or less cold air through conduit 22. If the compressor-turbine set is not to be used with another stove the motor 62 is shut off. If the set is to be used with another stove the motor 62 can continue to operate and valves 104, 106 and 108 opened to the other stove.

While one embodiment of my invention has been shown and described, it will be apparent that other adaptations and modifications may be made without departing from the scope of the following claims.

I claim:

1. A blast furnace stove comprising a hollow structure, checkerwork in said structure extending from a point adjacent the bottom thereof to a point adjacent the top thereof, a first conduit opening into said hollow struc-

ture adjacent the bottom thereof below the checkerwork, a valve for controlling flow of air through said first conduit into said structure, a second conduit opening into said hollow structure adjacent the bottom thereof below the checkerwork, a valve for controlling flow of burnt gases from said structure through said second conduit, a third conduit opening into said hollow structure above said checkerwork, a valve for controlling flow of heated air from said structure through said third conduit, said hollow structure having an upwardly extending opening through the top thereof, an inner shell basket mounted on top of said hollow structure around said opening with its axis substantially vertical, said inner shell basket having openings through its wall, an outer shell mounted on top of said hollow structure around said inner shell basket concentric therewith, a conduit for delivering fuel to the top of said inner shell basket, a conduit for delivering combustion air to the space between said inner and outer shells adjacent the top thereof, and valve means between said inner basket and the hollow structure.

2. A blast furnace stove according to claim 1 including a pilot burner at the top of said inner shell, a regulating valve for controlling flow of fuel in said fuel conduit, a regulating valve for controlling flow of air in said combustion air conduit, a temperature responsive device at the top of said checkerwork, and means controlled by said temperature responsive device to control said fuel regulating valve.

3. A blast furnace stove according to claim 1 including a regulating valve for controlling flow of fuel in said fuel conduit, a regulating valve for controlling flow of air in said combustion air conduit, a compressor for supplying fuel to said fuel conduit under pressure, a compressor for supplying air to said fuel conduit under pressure, and means for positioning the valve in said second conduit to maintain the burnt gases in said structure at a pressure substantially above atmospheric.

4. A blast furnace stove according to claim 3 including a gas turbine connected to drive at least one of said compressors, a conduit leading from said second conduit to the inlet of said gas turbine, and means for controlling flow of burnt gases from said second conduit to the inlet of said gas turbine.
